UNITED STATES PATENT OFFICE.

ELDRIDGE PACKHAM, JR., OF BALTIMORE, MARYLAND.

DESIGN FOR A FLASK.

SPECIFICATION forming part of Design No. 23,924, dated January 1, 1895.

Application filed November 27, 1894. Serial No. 530,194. Term of patent 14 years.

To all whom it may concern:

Be it known that I, ELDRIDGE PACKHAM, Jr., a citizen of the United States, residing in the city of Baltimore and State of Maryland, 5 have invented and produced a new and original Design for Flasks, of which the following is a specification.

My design for a flask is fully shown in the accompanying drawings, in which—

10 Figure 1 is a side elevation thereof. Fig. 2 is a transverse vertical section thereof.

My design for a flask consists essentially of a flask of substantially the shape shown, 15 ornamented with the outlines of an eye upon the side thereof, the whole presenting the general appearance of an eye.

A designates the body of the flask.

C, are the elevations forming the contour of the eyelids which inclose the depressions

20 forming the eye ball, D, within which are shown the iris, B, and the pupil, E.

My flask may be made of glass, opal, or other suitable material and may be of any color, or colors desired, the essential feature of the design being the flask ornamented upon 25 the side with curved elevations and depressions presenting the appearance of an eye.

I claim as my invention—

The design for a flask, substantially as herein shown and described.

30 In testimony whereof I have signed my name to this specification in the presence of two subscribing witnesses.

ELDRIDGE PACKHAM, Jr.

Witnesses:

CHARLES E. OUTRAM,
HENRY LIEBECK.
